UNITED STATES PATENT OFFICE.

WILLIAM C. UPP, OF NEW YORK, N. Y.

VIEW-CHANGING DEVICE.

1,090,121.

Specification of Letters Patent. Patented Mar. 10, 1914.

Application filed June 19, 1913. Serial No. 774,590.

To all whom it may concern:

Be it known that I, WILLIAM C. UPP, a citizen of the United States, and a resident of the city of New York, borough of Manhattan, in the county and State of New York, have invented a new and Improved View-Changing Device, of which the following is a full, clear, and exact description.

This invention relates to view changing devices and has particular reference to means for exhibiting cards, pictures or the like, in such a manner as to provide an automatic change from one view to another at regular intervals.

Among the objects of this invention, therefore, is to provide a machine including certain constantly rotated parts and an associated view carrier adapted to be operated intermittently in a regular way from certain of said moving parts, the movement of the view carrier being controlled by automatic means.

The foregoing and other objects of this invention will hereinafter be more fully described and claimed and illustrated in the drawings forming a part of this specification in which like characters of reference indicate corresponding parts in all the views, and in which—

Figure 1 is a side elevation of one form of the invention; Fig. 2 is a longitudinal vertical section of the same; Fig. 3 is a transverse section on the line 3—3 of Fig. 2, but on a larger scale; Fig. 4 is a transverse section on the line 4—4 of Fig. 2; Fig. 5 is a vertical section of a modification; Fig. 6 is a plan view of a view carrier corresponding to Fig. 5; Figs. 7 and 8 are detailed views of a card holder such as used in Fig. 5, the two views being at right angles to each other; Fig. 9 is a transverse section on the line 9—9 of Fig. 8; Fig. 10 is a detail indicating another modification adapting the device to lantern slides; and Fig. 11 is a fragmentary view of the face of one of the card holders covered by Fig. 10.

The several parts of the device as hereinbefore suggested may be made of various forms or designs, and the materials may be those best suited for their purpose as hereinafter set forth and specifically claimed. While for convenience of description I will hereinafter employ the term "card" as referring to the view, picture or the like, to be exposed to view, such term is to be taken in its broadest sense as being applicable to

any character or nature of device for this purpose.

At 10 I show a wheel secured rigidly in any suitable manner to a shaft 11 journaled in bearings in a frame 12 and adapted to be given a continuous rotation from a power shaft 13, the means for driving the shaft 11 being indicated as a worm wheel 14 and a driving worm 15.

At 16 I show a card carrier in the nature of a rim fitted to the periphery of the wheel 10. Said carrier is shown provided with a flange 17 extending inwardly and lying against the flat face of the periphery aforesaid. Said carrier 16 is adapted under normal conditions to be frictionally engaged to the wheel 10 and hence caused to rotate thereby. As a convenient means for effecting this engagement, I provide a plurality of spring fingers 18, each pivoted at 19 to the wheel 10 adjacent the hub thereof and having its free end overlapping the flange 17, and by virtue of the resiliency of the springs 18, the flange will be caused to grip against the periphery of the wheel 10 for the purpose above set forth so that unrestricted the card carrier or rim 16 will rotate with the wheel 10. As shown especially in Fig. 4 the inner end of each spring 18 is extended beyond the pivot 19 so as to engage the hub of the wheel 10 so as to prevent circumferential displacement of the card carrier due to the driving frictional engagement between it and the wheel. As shown in dotted lines, however, I may swing the springs 18 around their pivots so as to remove them from the flange 17 whereby the card carrier may be removed freely from the wheel.

Any suitable number or form of card holders 20 may be provided and pivotally connected to the carrier 16. In this form of the invention each card holder 20 is substantially rectangular and is provided with flanges 21 and 22 between which the card may be slipped and held during ordinary operation. Each holder also is provided with a pair of ears 23 which extend on opposite sides of the carrier 16 and through which a pivot pin 24 extends and connects the holder to the carrier. Each holder, furthermore, is arranged angularly, as shown at 25, whereby on the ascending side of the device each holder will be supported upon the pin 24 of the next holder whereby the several holders will be brought into a ra-

dial position with respect to the wheel while moving from its lowermost position to its uppermost position, as shown in Fig. 1. Each holder, however, will be free to be thrown over its pivot pin 24 at a predetermined time, and when so thrown over, the holder will lie in close relation to those in advance thereof in a substantially tangential position. Each holder also is provided with a finger 26 which extends inwardly from the pivot pin 24 for coöperation with a lug 27 secured in fixed relation to the frame 12 whereby, when the card carrier brings a holder into position for its finger 26 to contact the lug 27, the holder will be caused to swing quickly around the pivot pin 24 as from the upright radial position in Fig. 1 to the tangential position just at the right thereof.

20 A dog 28 is suitably arranged for slidable movement in a radial direction into engagement with the several pivot pins 24 for the purpose of automatically stopping the movement of the carrier with the wheel. Said dog 28, in Figs. 1, 2 and 3, is shown supported upon an extension 29 of the bracket to which the lug 27 is connected, but on the opposite side of the shaft 11 therefrom. The dog is provided with a cam 30 extending from one side thereof, and this is adapted to be engaged by a pin 31 carried by the wheel 10, whereby, upon engagement of the pin with the cam, the dog 28 will be lifted out of the path of the pins 24 whereby the carrier may be free to rotate with the wheel. As soon, however, as the pin 31 passes the cam 30, the dog 28 will be free to drop between the next two pins 24, and by being impinged by one of them will cause the stoppage of the carrier and the holding of it until the pin 31 again comes into coöperation with the cam. It will follow, therefore, that for each rotation of the wheel 10 the carrier will be given a partial rotation or step-by-step movement, causing the change from one view to the next due to the tilting of a card holder by means of the coöperation between the finger 26 and the lug 27.

50 The modification illustrated in Figs. 5 to 9, while embodying the same general principles as have already been set forth, is slightly different in detail, the same being adapted for the presentation to view of two cards or parts of the same view simultaneously. In this form of the invention the shaft 11' is upright, though inclined slightly from the vertical, and to it are connected two wheel parts 10^a and 10^b in spaced relation, the part 10^a, however, substantially corresponding to the wheel 10 above described and having the same form of spring fingers 18 connected thereto by pivots 19. The carrier likewise includes a pair of rims 16^a and 16^b, each having a flange resting upon the upper face of the corresponding

wheel portion. The card holder 20' in this form of the invention is preferably formed of a plate of metal having angularly arranged ends and extending between the carrier parts 16^a and 16^b and pivoted thereto by means of pivots 24^a and 24^b. Each holder 20' is shown provided with clips 21'. By virtue of the inclination of the shaft 11', the cards held by the respective holders tend to gravitate below the axis of said shaft, as shown in Fig. 6; that is to say, from the front or upper face of the device the holders tend to assume positions inclined to the right and left whereby the two holders 20' at the front are so arranged with respect to each other as to present a double view. In other words, each holder may carry two views, or two cards with views on opposite sides, so that the view on the front face of one card may be a continuation of the view on the back of the card in front. The pivot 24^b of each holder in this form is provided with a finger 26' adapted to engage a fixed lug 27' for the purpose of turning the holder around its axis. The pivot 24^a is extended far enough beyond the carrier 16' to engage with the dog 28' guided for radial movement with respect to the shaft 11, but in this case is provided with a spring 32. This dog, as before, is adapted to be withdrawn from engagement with the pivot 24^a by means of a cam 30' engageable by a pin 31' on the wheel 10^a.

The card holder 20^a is intended to carry a lantern slide which may be viewed through the central opening 33. These holders may be carried by a vertical wheel substantially in the same manner as shown in Fig. 1, and not being provided with the shoulders 25, they will lie substantially tangentially on both sides of the view point, as shown in Fig. 10. The finger 26^a, however, is so related to the lug 27 as to cause the several holders to be thrown successively around their axes through an angle of nearly 180 degrees, somewhat in the same manner as described in connection with Figs. 5 and 6. The stopping mechanism, however, is so arranged that the carrier will be stopped while each holder is in its mid position whereby there will be a practically unobstructed view through the holder as is necessary in connection with lantern slides. In order that there may be no interference between the fingers 26^a of adjacent holders 20^a they may be staggered so that the fingers of two adjacent holders may both be in engagement with the lug 27 at the same time.

Having thus described my invention, I claim as new and desire to secure by Letters Patent:—

1. In a view changing device, the combination of a shaft, means to rotate the shaft continuously, a wheel secured to the shaft and rotated continuously therewith, a card

carrier associated with said wheel, means to temporarily engage the carrier and hold it from movement, means to cause the carrier when unrestricted to rotate with the wheel, 5 a series of card holders carried by the carrier, and means operated by said wheel in conjunction with said carrier engaging means for automatically causing the carrier to have a step-by-step movement around the 10 axis of the wheel.

2. In a view changing device, the combination of a wheel, means to rotate the same continuously, a card carrier connected frictionally to the rim of the wheel for rotation thereby, a series of card holders carried by the carrier, and means coöperating with the carrier to momentarily stop its rotation, said last mentioned means being operated automatically from the wheel. 15

3. In a view changing device, the combination of a wheel, means to rotate the same continuously, a card carrier surrounding the wheel, a plurality of springs causing frictional engagement between the carrier 20 and the wheel, whereby the carrier under normal conditions will rotate with the wheel, a series of card holders carried by the carrier, each card holder having a projecting finger, a stationary lug adapted to be engaged by said finger to cause the rotation of the card holder while revolving with the carrier, and means to automatically cause the carrier to be given a step-by-step movement around the axis of the wheel. 25

4. In a view changing device, the combination of a wheel, means to cause the wheel to rotate continuously, a card carrier surrounding the wheel, a plurality of springs connected to the wheel and extending across

the carrier to cause the same to be given 40 frictional engagement with the wheel for normal rotation thereby, a series of card holders pivoted to the card carrier, each card holder being free to swing around its pivot while revolving with the carrier, and 45 means operated from the wheel for causing the carrier to be automatically stopped for imparting to it a step-by-step rotation.

5. In a view changing device, the combination of a wheel, means to rotate the 50 wheel continuously, a card carrier surrounding the wheel, a plurality of springs pivoted to the wheel, each spring having one end overlapping the carrier and its other end extending inwardly beyond its pivot 55 into engagement with the wheel hub, a series of card holders carried by the carrier, and automatic means to control the movement of the carrier with the wheel.

6. In a view changing device, the combination of a wheel, means to rotate the wheel continuously, a card carrier associated with the wheel, means to cause the carrier to rotate with the wheel, a series of card holders carried by the carrier, each card holder having a projecting pivot, a dog movable automatically radially with respect to the axis of the wheel, into engagement with said projecting pivot, and means carried by the wheel to momentarily withdraw the dog 70 from such engagement. 60

In testimony whereof I have signed my name to this specification in the presence of two subscribing witnesses.
